UNITED STATES PATENT OFFICE

SAMUEL RUBEN, OF NEW ROCHELLE, NEW YORK

ELECTRICAL PHONOGRAPH PICK-UP

Application filed October 24, 1930. Serial No. 490,903.

This invention relates to an electrical phonograph pick-up device for translating mechanically recorded acoustic vibrations into electrical undulations. An object of 5 the invention is the provision of a device for effecting such translation with minimum distortion and with an efficiency above that of the device of the prior art. This invention constitutes an improvement upon that described in my United States Letters Patent 10 Number 1,757,547.

Broadly, my invention consists of a device 15 for translating mechanically recorded acoustic vibrations into electrical impulses of corresponding frequencies, through changes in the resistance of a vanadium pentoxide electrode in response to pressure changes produced by the movement of a stylus vibrating through its contact with the surface 20 undulations upon a moving body, the undulations representing mechanically recorded acoustic vibrations. I have found that fused vanadium pentoxide has pressure electrical 25 resistance characteristics somewhat similar to those of cuprous oxide. It is these characteristics that are employed to effect the 30 translation of recorded sound vibrations into electrical oscillations. For translation with minimum distortion the vibratory electrode 35 is controlled by a resilient body as a means of "damping" the vibrations, and is in surface contact with a vanadium pentoxide electrode. In this device one of the electrodes 40 constitutes a stylus, one end of which is in contact with the record, the other electrode being a pentoxide layer upon each of two members in surface contact with the vibratory electrode. Or the vanadium pentoxide 45 layers may be upon opposite sides of the vibratory electrode in contact with fixed electrodes of another material. As the stylus oscillates in response to the movement of its pointed end in contact with the recorded undulations, the pressure upon the vanadium pentoxide varies, the current flow therethrough changing accordingly. With increased pressure upon the vanadium pentoxide electrode, 50 due to the negative contact resistance coefficient of this material with pressure, there

is an increase of current flow through the oxide.

The contact between the opposing electrode surfaces must be uninterrupted throughout the various pressure changes produced by the 55 movement of the stylus; this is secured by "damping" by the use of any suitable resilient material such as rubber; it also prevents excessive movement of the stylus. For maximum efficiency and minimum distortion 60 the push-pull or two-phase electrical arrangement is best adapted to this device.

For a better understanding of the invention reference is made to the accompanying drawing illustrating one embodiment thereof in 65 which Figs. 1, 2 and 3 represent different views of the device, Figs. 4 and 5 showing sectional views thereof. Referring more particularly to the drawing, at 1 is an insulating base upon which metal support 2, is mounted. At 3 70 is a needle or stylus rigidly mounted in a rotatable aluminum member 3_a, having a shaft 3_b which is mounted in a bearing in support 2, having a rubber lining at 4. To further damp the rotatable member a rubber blanket 4_a, is placed around it, particularly between that member and the variable 75 resistance button 9, here composed of thin layers of vanadium pentoxide, upon nickel bases 9_a which are held in position by screws 80 9_b. Screws 9_b are locked by screws 9_c. Contacting with resistance buttons 9 is conductive plate 5, mounted upon the aluminum member 3_a, outside of rubber blanket 4_a. The stylus 85 3, is connected in an electrical circuit by means of screw 6, lead 7 and terminal 8. The vanadium pentoxide buttons are connected in an electrical circuit by means of terminals 10.

In the operation of the device, its total 90 resistance is initially the combined contact and crystal internal resistance of vanadium pentoxide.

What I claim is:

1. A phonograph pick-up comprising a vibratory stylus and a pressure sensitive electrode composed of vanadium pentoxide, said electrode constituting a part of an electrical circuit and said stylus being adapted to vary the pressure on said electrode in accordance with mechanically recorded vibrations to 100

translate the latter into electrical undulations in the electrical circuit.

2. A device for translating mechanically recorded vibrations into electrical undulations comprising a base supporting a rotatably mounted stylus constituting a vibration responsive electrode, and a cooperating vanadium pentoxide electrode in surface contact with the other electrode.

10 3. A device for translating mechanically recorded vibrations into electrical undulations, comprising a base supporting a rotatably mounted stylus constituting a vibration responsive electrode, and a cooperating electrode in surface contact with the other electrode, one of said electrodes being composed of vanadium pentoxide, and means for damping the movement of the stylus.

20 4. A device for translating mechanically recorded vibrations into electrical undulations, comprising a base supporting a rotatably mounted stylus constituting an electrode, a vanadium pentoxide electrode held in surface contact with the other electrode by

25 a resilient body.

5. A device for translating mechanically recorded vibrations into electrical undulations, comprising a base supporting a rotatably mounted stylus constituting an electrode, a layer of vanadium pentoxide upon a nickel base, constituting another electrode and means for maintaining said electrodes in surface contact, said means comprising a resilient body.

35 6. A device for translating mechanically recorded vibrations into electrical undulations comprising a base support, a stylus constituting a vibratory electrode, a cooperating electrode having a plurality of members, each member being in surface contact with said stylus, one surface of each pair of said surfaces in contact being composed of vanadium pentoxide.

45 7. A device for translating mechanically recorded vibrations into electrical undulations comprising a base support, a stylus constituting a vibratory electrode, means for damping the movement of the stylus, said means comprising a resilient body, a cooperating electrode having a plurality of contact members, each in surface contact with said stylus, one surface of each pair of said surfaces in contact being composed of vanadium pentoxide.

55 8. In a phonograph pick-up, a stylus constituting a vibratory electrode, and a cooperating electrode having two contact members mounted in surface contact with the vibratory electrode, two of said electrode contacting areas being composed of vanadium pentoxide.

9. In a phonograph pick-up a stylus constituting a vibratory electrode, means for damping the movement of the stylus, comprising a resilient body and a cooperating

electrode having two contact members in surface contact with the vibratory electrode, two of the electrodes contacting areas being composed of vanadium pentoxide.

10. In a phonograph pick-up, a stylus constituting a vibratory electrode, and a cooperating electrode having two contact members mounted in surface contact with the vibratory electrode, two of said electrode contacting areas being composed of vanadium pentoxide, the vibratory electrode being so mounted that the movement of the contacting area of the vibratory electrode in one direction causes an increased contacting resistance of the vanadium pentoxide at one of said electrode contact areas and a decreased contact resistance at the other electrode contacting area.

75 11. In a phonograph pick-up, a stylus constituting a vibratory electrode, means for damping the movement of the stylus, said means comprising a resilient body, and a cooperating electrode having two contact members in surface contact with the vibratory electrode, two of the electrode contacting areas being composed of vanadium pentoxide, the vibratory electrode being so mounted that the movement of the contact area of the vibratory electrode in one direction causes an increased contact resistance of the vanadium pentoxide at one of said electrode contacting areas and a decreased contact resistance at the other electrode contacting area.

80 12. In an electrical phonograph pick-up a pressure sensitive electrode composed of vanadium pentoxide and means actuated by the undulations of the acoustic track of mechanically recorded vibrations to vary the pressure on said electrode.

90 13. A phonograph pick-up comprising a vibratory stylus and a pair of electrodes in pressure contact with each other, one of said electrodes being composed of vanadium pentoxide and said vibratory stylus being adapted to vary the pressure between said electrodes to translate mechanically recorded vibrations into electrical undulations in an electrical circuit including said electrodes.

95 14. A device for translating mechanically recorded vibrations into electrical undulations comprising a base, a pair of fixed spaced apart pressure sensitive electrodes mounted on said base, said electrodes being composed of a material, the contact resistance of which varies with the pressure applied, a stylus mount pivotally mounted on said base between said electrodes, a head forming a part of said stylus mount, a metallic bridging electrode mounted on said head of said stylus mount substantially conforming in shape to a portion of said head and being in pressure contact with said pressure sensitive electrodes, a rubber blanket interposed between said head of said stylus mount and said me-
